CLAIM

We claim the ornamental design for an LED track lighting module, as shown and described.

DESCRIPTION

FIG. 1 is a perspective view of an LED track lighting module embodying the invention;

FIG. 2 is a bottom view of the LED track lighting module of FIG. 1;

FIG. 3 is a left side view of the LED track lighting module of FIG. 1;

FIG. 4 is a front view of the LED track lighting module of FIG. 1; and,

FIG. 5 is a rear view of the LED track lighting module of FIG. 1.

The broken line disclosure represents portions of the LED track lighting module which form no part of the claimed design.

1 Claim, 3 Drawing Sheets
